UNITED STATES PATENT OFFICE.

WILLIAM H. HART, JR., OF PHILADELPHIA, PENNSYLVANIA.

FOLDER OR CONTAINER FOR GOODS.

1,073,117.

Specification of Letters Patent. Patented Sept. 16, 1913.

Application filed May 6, 1910. Serial No. 559,749.

To all whom it may concern:

Be it known that I, WILLIAM H. HART, Jr., a citizen of the United States, residing in the city and county of Philadelphia, State 5 of Pennsylvania, have invented a new and useful Folder or Container for Goods, of which the following is a specification.

My invention consists of a folder or device adapted to contain goods, such as articles of neckwear, gloves, ribbons and the like, the same being primarily of the order known as knock-down, and adapted to be opened, receive the goods and be closed in flat condition, thus containing the goods in 15 protective form, also convenient of carrying, packing, storing, etc., provision being made for inspecting the contents of the device without necessarily having access to the interior thereof, and for preventing the device 20 from opening and uncovering the contents of the same.

For the purpose of explaining the invention, the accompanying drawing illustrates a satisfactory reduction of the same to practice, but it is to be understood that the invention is not limited to the precise construction shown.

Figure 1 represents a perspective view of a folder embodying my invention, the same 30 being folded flat with a closing binder therefor. Fig. 2 represents a perspective view of the same partly open. Fig. 3 represents a perspective view of a portion of the device in blank form. Fig. 4 represents a perspective view of the members shown in Fig. 3, partly set-up.

Similar numerals of reference indicate corresponding parts in the figures.

Referring to the drawings: A designates 40 a folder which is composed of the quadrilateral bottom B, the side flaps C, the outer end flaps D, the latter being continuous with the bottom B, the inner end flaps E, the latter being continuous with the side flaps C, the 45 securing flaps F, on the terminals of the end flaps or turned-down folds D, and the triangular folds G, the latter being the end portions of the side flaps C creased on the lines H, the several members named being composed of a single piece of paper or cardboard. The folds or creases H form each 50 the hypotenuse of a right-angled triangle

one side of which is the end edge of the side flap C and which when said triangle is folded registers with the edge of the bottom B.

The end flaps E are inturned and overlap each other as shown at the left hand side of Fig. 2, and the flaps F are turned down on the top of said flaps E and secured thereto say by eyelets J, as shown at the right hand side of Fig. 2, this forming somewhat of a box shape structure in which goods such as articles of neckwear, gloves, etc., may be placed, after which the end flaps D and E are turned down on the bottom B on the goods resting thereon, this being permitted owing to the triangular folds F, G see Fig. 4. Then the side flaps C are turned down, the folds G disappearing below the same, said side flaps overlapping, the device presenting the appearance of a flat folder or casing in which the goods are contained as shown in Fig. 1, so that the goods are nicely packed and covered and 70 convenient for carrying. In the bottom B is an opening K through which the contents of the folder or casing may be seen, so that their quality, color or other characteristics may be made known without necessarily 80 opening the folder or casing, thus avoiding direct handling of the goods, and protecting the same from dust, especially when in stock.

In order to prevent the device from opening, I employ the binder L, which is of flat 85 tubular form and adapted to receive the folder or casing as a sheath so as to envelop the members of the device as shown in Fig. 1, said binder also covering the peep opening K as a closure therefor.

Having thus described my invention what I claim as new and desire to secure by Letters Patent, is:—

A knock-down folder, consisting of one piece of material comprising a bottom, side-flaps at the edges of said bottom, inner end-flaps continuous of said side-flaps and adapted to overlap, outer end-flaps continuous of the bottom and adapted to be folded on the outer sides of the inner end-flaps, and securing flaps upon the outer edges of said outer end-flaps and adapted to be folded inward over the edges of said inner end-flaps, the ends of the side-flaps being formed with

5 folds extending from the ends of the lower edges of the side-flaps to the upper edges of the latter to form each the hypotenuse of a triangle formed by folding the side-flap to bring its end-edge to register with its bottom-edge, whereby the end-flaps may be folded down on the bottom and the side-

flaps folded over the same to form a flat, rectangular knocked-down package.

WILLIAM H. HART, JR.
